J. HEINKEL

GARAGE DRAIN

Filed Jan. 13, 1922

INVENTOR.

John Heinkel
BY Walter N. Haskell,

his ATTORNEY.

UNITED STATES PATENT OFFICE.

JOHN HEINKEL, OF ST. LOUIS, MISSOURI.

GARAGE DRAIN.

Application filed January 13, 1922. Serial No. 523,989.

To all whom it may concern:

Be it known that I, JOHN HEINKEL, a citizen of the United States, residing at St. Louis, in the county of St. Louis and State 5 of Missouri, have invented certain new and useful Improvements in a Garage Drain, of which the following is a specification.

My invention has reference to garage drains, and aims to eliminate some of the 10 difficulties which now attend the use of such devices. On account of the vast amount of mud and filth that enters these drains, there is constant danger of their becoming choked up and inoperative. The chief purpose of 15 the present invention is to provide a means for preventing the mud and other sediment from entering the drain pipe, and interrupting its movement, so that it can be readily removed through the drain inlet, and dis- 20 charged. This is accomplished by supporting a receptacle removably in the upper part of the drain, which will receive the sediment, and which is fitted with overflow open- 25 ings which will permit the free escape of the water, without carrying the sediment with it. In connection therewith means is also provided for preventing the water from entering the drain with a whirling or twisting movement, such as would be likely to carry 30 it out of the receptacle.

The construction and arrangement of the device will more fully appear from the following specification, taken in connection with the accompanying drawing, which is 35 a sectional view of a drain for garage floors, equipped with the invention.

The reference character 1 indicates the main intake, adapted to be installed in the floor of a garage, and connected by a pipe 40 2 with the soil-pipe. The upper open end of the intake 1 is provided with a grating 3, to the under side of which is attached a bell-shaped spreader 4. Near its upper end the intake is provided with the customary 45 vents 5, below which is an annular ledge 6, upon which is removably supported a dish-shaped chute 7, in the lower part of which is an opening having an annular rim 8, to receive the rim of a bucket shaped recep- 50 tacle 9, provided near the top with a series of openings 10. The receptacle 9 is also

fitted with a handle 11, by means of which it can be removed from the chute.

In operation, the water rushes through the grating 3, where it is distributed in all 55 directions by the spreader 4, being again collected by the chute 7, and directed into the receptacle 9. Any sediment contained in the water finds its way to the bottom of the receptacle, while the water flows downwardly 60 into said receptacle, and then upwardly and out through the holes 10, passing thence to the lower part of the intake, and out through the pipe 2.

The action of the spreader 4, directing the 65 volume of water outwardly, and of the chute 7, the flaring sides of which direct it inwardly again, has the effect of causing the water to follow a straight course, instead of assuming a whirling movement, as would be 70 likely to be the case were such parts not employed. Such a whirling action would be likely to carry more or less of the sediment out of the receptacle 9 again, and into 75 the main drain.

Whenever desired, the grating 3 can be displaced, and the receptacle 9 removed and emptied of its contents. By this means a limited amount, if any, of the sediment will find its way into the soil pipe, and the same 80 will not become filled therewith. Such portion of the sediment as may find its way out of the receptacle 9 will be likely to settle in the intake 1, from which it can be removed. When it is desired to do this, not 85 only the grating with the spreader attached, and the receptacle 9, but the chute 7 can also be removed, leaving the intake practically clear of obstructions.

What I claim, and desire to secure by 90 Letters Patent, is:

1. A device of the class described, comprising an intake casing, provided with means for connection with a main drain; a grating for said intake, removably supported therein; a bell-shaped spreader supported just beneath said grating; a chute supported beneath said spreader, and possessing a diameter greater than that of the spreader; and a receptacle supported in the lower end 95 of said chute, provided with a series of openings near the top thereof.

2. A device of the class described, comprising an intake casing provided with means for connection with a main drain; a grating removably supported in the upper 5 part of said casing; a bell-shaped spreader secured to the lower face of said grating; a dish-shaped chute removably supported at a point below said spreader; and a container removably held in the lower part of said chute, and provided with overflow openings at its upper end.

In testimony whereof I affix my signature.

JOHN HEINKEL.
